UNITED STATES PATENT OFFICE.

HENRY C. MAUL, OF DETROIT, MICHIGAN, ASSIGNOR TO THE MICHIGAN STOVE COMPANY, OF DETROIT, MICHIGAN, A CORPORATION OF MICHIGAN.

VALVE.

1,171,622.

Specification of Letters Patent. Patented Feb. 15, 1916.

Application filed September 30, 1915. Serial No. 53,382.

To all whom it may concern:

Be it known that I, HENRY C. MAUL, a citizen of the United States of America, residing at Detroit, in the county of Wayne 5 and State of Michigan, have invented certain new and useful Improvements in Valves, of which the following is a specification, reference being had therein to the accompanying drawings.

10 This invention relates to valves for water heaters utilizing gas as a fuel, and more particularly to that type of valve automatically operated by water pressure to open and close a valve controlling the supply of 15 gas to the burner of the water heater. A common type of this valve has water and gas valves separated by stems passing through packing boxes susceptible to leakage, excessive friction, necessitating repeated repairs. Besides, there is a possibility 20 of water entering gas connections, or gas entering water connections, either of which require attention.

These and other defects have been noted 25 and it is the primary object of my invention to eliminate faulty construction by providing a valve, which is positive in its action, sensitive to the least fluctuation in water pressure, devoid of packing or elements that must be repeatedly renewed, composed of parts that can be easily and quickly assembled by unskilled labor, and, 30 highly efficient as an automatic control of a water heater.

35 My improvements will be better understood when reference is had to the drawing, wherein—

Figure 1 is a vertical sectional view of a valve in accordance with my invention, and 40 Fig. 2 is a horizontal sectional view of the same taken on the line II—II of Fig. 1.

The valve comprises a gas chamber 1, an intermediate atmospheric chamber 2, and a water chamber 3, said chambers being 45 superposed with a flexible diaphragm 4 forming the bottom of the water chamber 3 and a flexible diaphragm 5 forming the top or roof of the gas chamber 1. The gas chamber 1 is somewhat bowl 50 shaped and has a side connection 6 as an inlet for gas. The bottom of the chamber 1 has a gas outlet connection 7 and an annular groove 8 for a valve seat 9 made of fiber. The top of the gas chamber 1 has an

annular shoulder 10 for a gasket 11 and the 55 marginal edges of the diaphragm 5. Resting upon the marginal edges of the diaphragm 5 is a cylindrical shell 12 forming the walls of the intermediate atmospheric chamber 2, and this shell is provided with 60 a series of openings 13 and a plurality of articulated ribs 14, said ribs constituting a spider within the chamber 2.

The water chamber 3 is somewhat dome shaped and has a side water inlet connection 65 15 and a flushing connection 16 which is diametrically opposite the water inlet connection, whereby the water chamber 3 may be flushed and sediment or other foreign matter removed therefrom. The flushing 70 connection 16 is adapted to be closed by a faucet, similar to the drain pipe of an ordinary water boiler. The top of the water chamber 3 has a water outlet connection 17 and the bottom of said chamber has an annular shoulder 18 for a gasket 19, the marginal edges of the diaphragm 4, and the 75 upper end of the shell 12. The confronting ends of the chambers 1 and 3 have apertured lugs 20 connected by bolts 21 constituting a 80 conventional means of holding the three chambers in a superposed assembled position.

The diaphragms 4 and 5 are made of sheet brass or a similar material that can be 85 warped or flexed and to increase such action the diaphragms are provided with annular beads 32 contiguous to the marginal edges thereof. The diaphragms are disposed in parallelism and have concentric 90 vertically alining openings 33 providing clearance for a threaded gas valve stem 22. The lower end of the stem 22 has a nut 23 and a ball and socket connection 24 for a gas valve 25 adapted to evenly engage the 95 seat 9 at the bottom of the gas chamber 1. The fiber seat 9 coöperates with a sharp annular edge 26 of the valve in establishing a non-leakable shut off for gas when the valve is closed.

100 The gas valve stem 22 is screwed into the stem sections 27 and 28 of a water valve 29 reciprocable in the chamber 3. The stem section 27 is hexagonal in cross section or provided with suitable facets to facilitate 105 screwing said stem section on the gas valve stem 22. This stem section coöperates with the nut 23 in holding the gas valve relative

to the diaphragm 5 and coöperates with the stem section 28 in holding the water valve 29 relative to the diaphragm 4. The stem section 27 is disposed axially of the chamber 2 extending through the spider, and is encircled by a coiled compression spring 30, which bearing against the spider and engaging the diaphragm 5, holds the gas valve normally closed. The water valve 29 has the 10 form of a disk provided with depending lugs 31 engaging the walls of the water chamber 3 and guiding said valve in its movement.

In operation, the principle involved is 15 practically the same as any ordinary automatic water heater valve, that is, a reduction of water pressure above the water valve 29, caused by opening a hot water faucet, the pressure of water below the valve 29 raises 20 said valve, against the action of the spring 30 and opens the gas valve 25, thereby allowing gas to flow to the burner of a water heater and be ignited by the usual pilot light. An equal water pressure above and 25 below the water valve 29, caused by the closing of a hot water faucet, closes the gas valve 25, the pressure of water upon the diaphragm 4 coöperating with the spring 30 in this operation.

30 If during the operation of a water heater there should be a break in a city main or the water be unexpectedly shut off, then the tension of the spring 30 is sufficient to close the gas valve and prevent asphyxiation or 35 other accidents incident to the escape of gas.

Considerable importance is attached to the use of two diaphragms and the intermediate atmospheric chamber 2. Should there be 40 leakage at the marginal edges of the diaphragm or at either of the valve stems, the intermediate atmospheric chamber allows gas and water to escape without water entering the gas chamber or gas entering the water chamber, but if the casing parts of 45 the valve are properly assembled, such leakage is impossible. This has been demonstrated by an actual test of over thirty thousand operations sufficient in number for years of service, and it has been further 50 found that two diaphragms insure a very sensitive action of the valve and increase the longevity of the same. In operation it has also been found that when a hot water faucet is partially open that the water valve 29 is 55 shifted approximately a thirty second part of an inch and establishes communication between the lower part of the water chamber and the upper part thereof and that when the faucet is wide open the water valve has 60 been moved a sixteenth part of an inch. Such movement retains the lugs 31 of the water valve in engagement with the walls of the chamber 3, whereby the valve cannot become accidentally displaced, yet provides 65 sufficient communication between the upper

and lower parts of the water chamber to establish a free flow of water through a heating coil to a hot water faucet.

In closing the water valve 29 and seating the gas valve 25, excessive warping or flexing of the diaphragms 4 and 5 is prevented 75 by the upper edges of the rib 14 being below and in proximity to the diaphragm 4, thus eliminating any danger of the diaphragms being cracked or injured.

It is thought that the operation and utility of the valve will be apparent without further description, and while in the drawing there is illustrated a preferred embodiment of my invention, it is to be understood 80 that the structural elements are susceptible to such variations and modifications as fall within the scope of the appended claims.

What I claim is:—

1. A valve of the type described comprising 85 a casing, a gas valve in a part of said casing adapted to control passage of gas therethrough, a water valve in sliding engagement with the walls of said casing adapted to control passage of water thereto, 90 parallel diaphragms in said casing coöperating with said casing in forming an atmospheric chamber, said diaphragms adapted to cause said valves to move equidistant in synchronism, means between said diaphragms holding said gas valve normally closed, and means coöperating with said holding means adapted to limit the movement of said diaphragms in one direction. 95

2. A valve of the type described comprising 100 a casing, a gas valve in a part of said casing adapted to control passage of gas therethrough, a water valve in another part of said casing adapted to control passage of water therethrough, spaced parallel diaphragms between said valves adapted to cause said valves to move in synchronism, said diaphragms coöperating with said casing in forming a chamber in communication 105 with the atmosphere whereby gas leakage 110 in said casing may escape to the atmosphere, and means between said diaphragm holding said gas valve normally closed.

3. A valve comprising a gas chamber having 115 gas inlet and outlet connections, a water chamber having water inlet and outlet connections, a valve in each chamber, an intermediate chamber providing an outlet for leakage of gas and water in said valve, a spider in said chamber, diaphragms forming 120 the top and bottom of said intermediate chamber, means connecting said valves and said diaphragms and devoid of stuffing boxes to cause said valves to move in synchronism, and means engaging said spider 125 and one of said diaphragms adapted to hold said gas valve normally closed.

4. A valve of the type described, comprising 130 a gas chamber having gas inlet and outlet connections, a water chamber having

water inlet and outlet connections, an intermediate atmospheric chamber between said gas and water chambers affording an outlet for escaping gas and water in said valve, 5 diaphragms forming the top and bottom of said atmospheric chamber held in place by said gas and water chambers, valves in said gas and water chambers, and valve stems interlocked with said diaphragms to 10 cause the valves to move in synchronism.

5. A valve of the type described comprising a gas chamber having gas inlet and outlet connections, a water chamber having water inlet and outlet connections, an atmospheric chamber between said gas and water chambers affording an outlet for 15 escaping gas and water in said valve, diaphragms forming the top and bottom of said atmospheric chamber held in place by 20 said gas and water chambers, means connecting said gas and water chambers to maintain said atmospheric chamber therebetween, valves in said gas and water chambers, and a sectional valve stem interlocked 25 with said diaphragms to cause said valves to move in synchronism.

6. An automatic water heater valve comprising a gas chamber having gas inlet and outlet connections, an intermediate atmos-

pheric chamber on said gas chamber as an 30 outlet for gas leakage in said valve, a diaphragm between said chambers, a water chamber on said intermediate atmospheric chamber having water inlet and outlet connections, a diaphragm between said water 35 chamber and said intermediate chamber, a gas valve in said gas chamber, a threaded stem having a ball and socket connection with said gas valve, a water valve in said water chamber above the water inlet connection 40 with said chamber and having a sectional stem in screw-threaded engagement with the stem of said gas valve and holding said diaphragms relative to said gas valve stem, a spider in said atmospheric chamber 45 adapted to limit the movement of said diaphragms in one direction by one of said diaphragms contacting therewith, and means between said spider and one of said diaphragms adapted to hold the gas valve normally closed. 50

In testimony whereof I affix my signature in presence of two witnesses.
